Patented Apr. 26, 1921.

UNITED STATES PATENT OFFICE.

LEWIS A. CHAMBERLIN, OF DE SOTO, MISSOURI.

HEEL-FASTENING DEVICE.

1,375,897.

Specification of Letters Patent. Patented Apr. 26, 1921.

Application filed March 15, 1920. Serial No. 365,854.

To all whom it may concern:

Be it known that I, LEWIS A. CHAMBERLIN, a citizen of the United States, residing at De Soto, in the county of Jefferson and State of Missouri, have invented certain new and useful Improvements in Heel-Fastening Devices; and I do declare the following to be a full, clear, and exact description of the invention, such as will enable others skilled in the art to which it appertains to make and use the same.

This invention relates to an improved heel fastening device especially designed for permanently securing wooden heels to shoes, slippers, and the like, but not to be restricted to this particular use since it will well serve to connect many other members together.

Ordinarily, wooden heels, such as French heels, are secured to the upper, or rather to the sole, by glue. They are also fastened in place by nailing, both methods being crude and unsatisfactory because in most cases, if the heel is glued in place it does not stay on long, especially if it is hit against obstructions, such as curbs, car steps and the like, which accidents often occur. When they are nailed, or similarly fastened on, they stay on better, but this method is bad because the heels are so often split during their attachment to the upper. The last method is expensive because the split heels have to be thrown away.

It is my intention and the object of this invention to overcome the above unnecessary circumstances by the employment of novel fastening means which will permanently secure the heel in place and yet obviate the liability of the heel becoming split by its use; the fastening means being such that it will facilitate the attachment of heels, because of the fact that it will clamp the heel in place while the glue sets, also, because the fastening will be effected by merely forcing the heel and sole together. In view of the fact that it is placed in the strongest part of the heel it will overcome my possibility of the heel splitting.

Another object of the invention is to provide a heel fastening device which is simple and effective, strong, durable, and inexpensive; one which will reinforce the heel, and which is such that it will enable unskilled persons to put on their own heels.

Other objects and advantages of the invention will be apparent during the course of the following description.

In the accompanying drawings forming part of this specification and in which like numerals are employed to designate like parts throughout the same:—

Figure 1 is an elevation, partly in section, of a fastening device constructed in accordance with my invention, the parts being shown in the position they assume just before the heel is attached.

Fig. 2 is a sectional view thereof showing the position of the parts when the device is effective.

Fig. 3 is a top plan view of one of the parts of the fastener.

Fig. 4 is a detail perspective view of the parts of the fastener.

In the drawings, wherein for the purpose of illustration is shown a preferred embodiment of my invention, the numeral 1 designates a portion of the upper of a shoe or slipper and the numeral 2 denotes the sole thereof. Indicated by 3 is a wooden heel of the "French heel" type with which my improved fastener is shown in use.

My improved fastening device includes a cylindrical stud 4 which is formed in its lower end with a socket and is carried by a non-circular plate 5. The latter is adapted for attachment to the exterior of the sole 2, while the stud is designed to be projected into a vertical socket 6 formed in the upper portion of the heel 3. The lower end of the socket is undercut at 7 to produce a continuous shoulder, and a cone-shaped spreader 8 including a flat circular base is to be placed in the bottom of this bore or socket to expand the lower edge of the stud beneath said shoulder when the heel and sole are forced together sufficiently hard enough. In addition to the socket, the heel is also provided in its upper face with a recess 9 corresponding in shape to the aforesaid plate, being adapted for reception of the plate 5, which construction prevents twisting or rotation of the heel with respect to the shoe upper.

When it is desired to attach a heel with my improved fastening means, it will be necessary to first secure the plate 5 to the under face of the shoe sole in the manner shown. Next, the heel will be brought in play by inserting the stud 4 into the socket 6, whereupon the heel and sole members will be forced together so as to cause the lower end of the tube to engage the base of the spreader 8 and expand in the manner shown

in Fig. 2. The heel will then remain permanently in place. It is to be understood that the spreader 8 may either be placed in the socket before the sole and heel are brought together, or, it may be forced into the end of the tube 4 preparatory to the fastening of the heel. Either way will be satisfactory.

My heel fastening device will be found extremely useful and satisfactory in many respects because it will permit the heel to be easily and readily attached. Furthermore it will reinforce the heel rather than weaken it as the ordinary nail fastenings do. It is light in weight and will take the place of a clamp, in that it will hold the heel tightly in position while the glue sets. Then again, it will positively prevent splitting of the heel when the latter is being attached. Not only that, but it will retain the heel in place much longer than the fastenings now in use.

A careful consideration of the foregoing description taken in connection with the accompanying drawings will enable the reader to acquire a clear understanding of the construction and use of the device. In view of this, it is believed that a more lengthy description is unnecessary.

It is to be understood that the form of my invention herein shown and described, is to be taken as a preferred form of the same and that various minor changes in the shape, size, and arrangement of parts may be resorted to without departing from the spirit of the invention or the scope of the subjoined claims.

I claim:

1. In combination, a shoe including a sole, an attaching plate secured to the under face 40 of the heel attaching portion of the sole, a heel formed in its upper face with a recess receiving the plate therein, said heel being also provided with a vertical socket, the inner end of which is increased in diameter 45 to provide a continuous shoulder, a depending stud rigidly connected to the attaching plate and extending into the socket, having a socket formed in its lower end, said stud being eccentrically disposed with respect to the periphery of the plate, and a conical 50 spreader seated in the bottom of said first socket and extending into the socket in said

stud, serving to expand the lower edge of said stud beneath the shoulder when the heel is forced against the sole. 55

2. A device of the class described comprising a non-circular flat attaching plate provided with a central laterally and eccentrically disposed solid cylindrical stud formed at its lower end with a socket, the lower end of said stud being continuous and uninterrupted, said plate being intended for permanent connection to a member, a second member designed to bear tightly against and be connected to said first named member, 60 said second member being formed with a central vertical cylindrical socket adjacent its upper end, the inner end of said socket being undercut to form a continuous uninterrupted shoulder, said stud being adapted to extend 7 into the socket and slightly beyond the shoulder, the last named member having a shallow recess formed in its upper face of a shape corresponding to the aforesaid plate, said recess being intended to receive the 7 plate therein and prevent relative rotation of the members and in turn prevent rotation of the stud in the socket, and a spreader seated in the socket including a conical portion to extend into the socket in the lower 8 end of said stud and a base having a flat upper face intended to roll the inner end of the stud when the two members are forced together so as to form a continuous uninterrupted retaining bead which will extend 8 beneath said shoulder and connect the members together.

3. A fastening device of the class described comprising attaching means, a laterally disposed cylindrical solid stud rigidly connected thereto, being formed in its lower end with a socket, a member including a socket into which the stud extends, the inner end of said socket being enlarged to provide a continuous shoulder, and a spreader disposed in the socket, including a conical portion to extend into the socket in the stud, and a flat circular base for engaging and rolling the lower edge of said stud beneath the shoulder, thereby forming a continuous retaining bead.

In testimony whereof I have hereunto set my hand.

LEWIS A. CHAMBERLIN.
